Patented May 21, 1918.

UNITED STATES PATENT OFFICE.

JOSEPH F. RIOUX, OF EDGEWOOD, RHODE ISLAND.

BUCKLE.

1,266,629.

Specification of Letters Patent. Patented May 21, 1918.

Application filed July 4, 1917. Serial No. 178,522.

To all whom it may concern:

Be it known that I, JOSEPH F. RIOUX, a citizen of the United States, residing at Edgewood, in the county of Providence and 5 State of Rhode Island, have invented a new and useful Improvement in Buckles, of which the following is a specification.

This invention relates to certain new and useful improvements in a buckle especially 10 adapted for personal use with belts, and it has for an object to provide a buckle having means to adjustably retain each end of the belt in close relation so as to render same comfortable to the wearer.

15 Further, the invention resides in an improved buckle having a main securing member to which the anchoring member is connected and by which it is carried; each member adjustably engaging a respective end of 20 the belt in such manner as to better secure or engage the same when the latter is under a strain or pull.

The invention further resides in the specific features of construction and the arrangements of parts hereinafter described 25 and claimed, reference being had to the accompanying drawing wherein—

Figure 1 is a front elevation of the improved buckle attached to a belt, the latter 30 being shown in fragment.

Fig. 2 is a longitudinal section thereof disclosing the belt-engaging means operatively related.

Fig. 3 is a rear elevation of the disclosures 35 made in Fig. 1, and

Figs. 4 and 5 are transverse sections on lines 4—4 and 5—5, respectively, of Fig. 2 showing the belt gripping means for each end of the belt.

40 Referring more particularly to the drawing, the body 1 of the buckle comprises a front face plate curved longitudinally to conform to the shape of the body and provided on its upper and lower edges with 45 turned walls or flanges 2. The body walls have a pair of opposing bearings 3 in which are journaled the trunnions 4 of a clamp 5, said clamp being more or less in the form of a T, in cross section with the trunnions dis- 50 posed at one edge or side of the cross bar. The stem of the T-clamp is also slightly curved and has the trunnion-bearing flange 6 extending therefrom toward the opened side of the body with the flange 7, which is 55 preferably sharpened, extending in an opposite direction or inwardly toward the

front plate for clamping the belt thereagainst.

The stem portion of the clamp is in the form of a broad plate that extends from the 60 jaw or belt-engaging part 7 to lie beyond the ends of the body walls, when said clamp is operative. On the projecting free end of the clamp and turned up from the upper and lower edges thereof, are a pair of ears 8 having coinciding bearings 9 for supporting the trunnions 10 of a belt anchoring clamp 11. This clamp is of bell-crank in design, having a short arm or jaw part 12, which is 65 preferably serrated, and a longer, operating 70 lever or handle which extends toward the flange 6, the latter being formed on its free edge with an overhanging lip or keeper 13 beneath which the free end of the handle part of clamp 11 is adapted to spring or 75 engage for guarding said free end and prevent accidental and unauthorized lifting thereof.

In practice, the fixed end of the belt 14 is inserted between the serrated edge 12 and 80 the comparatively stationary jaw plate formed by the handle lever of clamp 5, and the clamp 11 moved to its operative position and secured therein by springing the handle thereof beneath the keeper 13. The belt is 85 then passed about the body and the free end threaded between the jaw part 7 and the front plate after which the handle part is swung toward said front plate to clamp the belt. The double clamp constitutes a 90 unitary device in which the anchoring clamp has its operating lever engaged by a snap catch or keeper and is pivotally mounted between the side walls of the body to actuate the gripping jaw 7. 95

Thus, the anchored end of the belt may be fixed in the desired position and the free end removably secured, both ends having adjustable securing. This is especially advantageous, as the belt can be fitted to 100 the customer from a stock of one length instead of, as at present, having to select from a stock of varying and many lengths.

Having thus described my invention, what I claim as new and desire to secure by Letters Patent is—

1. In a belt buckle, a body, a substantially rigidly formed T-shaped member having its cross-bar pivoted to the body so as to clamp one end of the belt between the 110 body and one side edge of the cross bar, a substantially L-shaped clamping member

pivoted to the T-shaped member adjacent the free end of the stem of the latter to clamp the opposite end of the belt between the stem of the T-shaped member and the 5 foot of said L-shaped member, and means to latch the free end of the stem of the L-shaped member to the opposite side of the cross-bar of the T-shaped member.

2. In a belt buckle a body, a rigid member pivoted adjacent one end to the body to clamp one end of the belt thereto, means 10 borne by said member to clamp the opposite end of the belt to one side face of said member, and means to latch said clamping 15 means to the member adjacent the first named end thereof.

3. In a buckle, a body, a rigid plate-like member pivoted at one end to the body and having means at said end to clamp one end 20 of the belt to the body, and a plate-like member pivoted at one end to the first named member and having means at said end to clamp the other end of the belt to the first named member, the first member 25 having a keeper adjacent its said first named end to enable the opposite end of the second member to be snapped into engagement thereto to latch the latter.

4. In a belt buckle, a body, a plate pivoted

at one end to the body and having means to 30 clamp one end of the belt thereto, said plate in clamping position extending substantially parallel to the body so as to extend in close juxtaposition throughout its length to said belt end, and a second plate pivoted at one 35 end adjacent the opposite end of and to the first plate and having means to clamp the other belt end to the first plate, said second plate extending in close juxtaposition to the first named plate.

5. In a buckle, a body, a member pivoted to the body to clamp one end of the belt thereto, and a second member superposed on and operatively connected to the first member so as to be borne by the latter to 40 clamp the other end of the belt to the first member, said members lying in close relation to and approximately parallel to the body so as to hold the belt ends flat and all 45 of the parts closely related.

In testimony whereof I have signed my name to this specification in the presence of two subscribing witnesses.

JOSEPH F. RIOUX.
